UNITED STATES PATENT OFFICE.

GERALD R. LIVERGOOD, OF HOUSTON, TEXAS.

PUMP PLUNGER.

1,425,398.

Specification of Letters Patent. Patented Aug. 8, 1922.

Application filed July 29, 1921. Serial No. 488,311.

To all whom it may concern:

Be it known that I, GERALD R. LIVERGOOD, a citizen of the United States, residing at Houston, Harris County, Texas, have invented a certain new and useful Improvement in Pump Plungers, of which the following is a full, clear, and exact description, such as will enable others skilled in the art to which it appertains to make and use the same.

10 My invention relates to pump plungers for use particularly in deep wells. It is adapted for the handling of oil or water where sand and sediment is encountered in the fluid being pumped.

15 The object of my invention is to provide a pump plunger so constructed as to operate for long periods in the pumping of liquid containing sand or other abrasive material without the usual amount of wear upon the 20 plunger or working barrel of the pump.

Another object is to provide means, on the plunger of a pump, adapted to scrape the sand away from the working barrel in combination with a wear-resisting packing ring 25 on the plunger to maintain a tight closure with the working barrel for long periods without necessity of renewal.

Another object is to provide an improved means, by the use of which my plunger may 30 be introduced into the tubing and working barrel.

These and other objects and advantages will more clearly appear from the detailed description which follows.

35 Referring to the drawing herewith wherein like parts are designated by like numerals of reference in the several views: Fig. 1 is a central longitudinal section through a length of tubing and working barrel showing my 40 plunger in elevation therein. Fig. 2 is a central longitudinal section through the plunger. Fig. 3 is a similar section through my plunger attachment. Figs. 4, 5, and 6 are plan, section and side elevation views respectively 45 of my packing means.

The construction of the main body of my plunger has been devised for purposes of greatest efficiency and convenience. There is a central tubular section or barrel 1 the 50 walls of which are thickened at the lower end 2. Said end 2 may be flattened on opposite sides as shown at 4 in Fig. 1 to supply a wrench hold. Above the end 2 and adjacent thereto is a small radial flange 3 providing a shoulder to receive the packing means. At 55 the upper end the barrel 1 is screwed within

a head 5 which is threaded interiorly at its lower end to receive it. The head 5 is reduced in diameter at its upper end and threaded for attachment to the valve cage 6 of ordinary construction.

Within the cage and resting on the upper end of the section 1 is a tightly fitting valve seat 7 shaped to receive a ball valve 8 thereon.

65 The means by which I maintain a close fit between the plunger and the working barrel of the pump comprise scrapers at the upper and lower ends of the plunger and resilient rings between the scrapers. The 70 scrapers include a cup 9 having a spacing sleeve 10 between it and the lock nut 11 threaded on the barrel below the valve cage at the upper end of the said barrel. The cup 9 is made of some resilient and wear-resisting material and is flared outwardly 75 somewhat at the upper end. The edge is sharpened to provide a scraper to wipe or scrape the sand away from the inner face of the working barrel. There may be one or 80 more of these cups at each end and I have shown two at the upper end. The cups are held apart by a spacer 10 so that the upper cup is clamped between the two spacing sleeves and the second one is clamped between one spacer and a sleeve or washer 12 which is recessed slightly on its upper face to 85 receive said cup.

At the lower end is a similar cup 9' with its flaring, scraping end presented downwardly. It is clamped between the flange 3 and a slidible ring or collar 13.

90 Between the cups 9 and 9' are a series of rings or collars 13 adapted to fit upon said section 1 and to bear against the inner face 95 of the working barrel 14 as shown in Fig. 1. One end of the rings 13 is recessed or reduced in diameter to provide a seat for a resilient expanding piston ring 15 of special 100 make but the exact construction of which constitutes no part of the present invention.

This piston ring is normally expanded and has to be compressed to be introduced into the working barrel after which its resiliency keeps it expanded to fit against the working barrel and sustain the weight of the column of liquid being pumped. These rings will wear for long periods of time without any marked loss in efficiency especially if the sand is kept from contact therewith. An important feature of my invention, therefore, is the combination of a pis- 105 110

ton ring mounted as shown, with scraping cups to prevent the entrance of sand from above or below the plunger so as to score the rings and working barrel.

5 In operating my improved type of pump plunger the cups and rings are assembled on the barrel of the plunger in the manner shown in Fig. 2 and the lock nut 11 is screwed down against the upper spacer 10 so as to clamp the cups and rings between the nut and the lower flange 3. The head 5 and the valve cage are then secured upon the upper end of the barrel and the plunger is then attached to the lower end of the 15 sucker rod 16 and is then ready to be inserted into the well.

When the rings are thus assembled they are in expanded position and the cups also are flared outwardly so that the plunger 20 will not readily enter the working barrel. To hold the rings and cups in contracted position so that they may be inserted downwardly through the tubing and into the upper end of the working barrel I provide a 25 guide barrel 17. This barrel comprises a short length of pipe having thin walls and of such length as to cover the outer surface of the plunger. At the upper end of this 30 guide barrel I form a slight inwardly projecting flange 18. At the other end of the barrel I provide a removable collar 19 recessed at 20 to receive the guide barrel, the 35 other end being somewhat bell-shaped to provide a tapered mouth to receive the cups and rings of the plunger. In the use of this 40 barrel the plunger is detached from the sucker rod and is inserted upwardly through the bell-shaped lower end of the barrel. The mouth of the collar 19 is large enough 45 to receive the rings of the plunger and to compress them inwardly so that they will be received within the guide barrel. When the barrel has been thus shoved downwardly over the plunger so as to compress all of 50 the rings and the cups, the collar 19 is removed from the guide barrel and the plunger is ready to go into the well. It is attached to the sucker rod and lowered downwardly until the working barrel 14 is 55 reached. The tubing 21 is of slightly larger internal diameter than is the working barrel. When the plunger reaches the working barrel, the lower end of the guide barrel 17 comes in contact with the upper end thereof and is prevented from further movement 60 downwardly. The plunger then passes through into the working barrel leaving the guide barrel standing on the upper end of the working barrel as shown in Fig. 1.

60 When the plunger is withdrawn again from the well it will come in contact with the guide barrel and with the flange 18 at the upper end thereof and thus bring it

with it to the surface where it may be removed.

In the operation of the pump in the well, the lower cups 9' will act to scrape away from the working barrel sand which might otherwise work up between it and the plunger, and in that way protect the expanding 70 rings. At the upper end of the plunger the cups 9 perform the same service. The rings thus protected from sand will maintain a tight closure with the working barrel at all times and preserve the necessary close fit 75 between these two parts which is necessary for the proper operation of the pump.

In the ordinary construction of pump plungers there is a nut at the lower end thereof which is threaded into contact with 80 barrel 1; but by the construction shown and described, whereby the lower end 2 and the barrel 1 are made integral, and whereby the barrel 1 is threaded at its upper end to the head and a locking nut 11 used thereon, there 85 is almost no danger of the loosening of the threaded portions so as to cause the loss of parts of the plunger in the well. This structure is, therefore, of importance due to the 90 fact that there is no danger from this construction of the loosening of the connections due to the jarring of the plunger against the foot valve or other parts of the structure during its operations.

Having thus described my invention, the 95 further objects and advantages of which will be obvious to one skilled in the art, what I claim as new and desire to protect by Letters Patent, is:—

1. In a pump, a working barrel, a plunger 100 reciprocable therein, a head on said plunger, a tubular barrel of smaller diameter than said head having threaded attachment with the lower end of said head, a flange at the lower end of said barrel, a cup of rigid 105 material at the upper end of said barrel adjacent said head, having a sharp upwardly directed scraping edge adapted to bear against the working barrel, similar cups at the lower end adjacent said flange having 110 the scraping edge directed downwardly, and hard metal expansion rings on said barrel between said cups.

2. In a pump, a working barrel, a plunger 115 reciprocable therein, a head on said plunger, a tubular barrel of smaller diameter than said head secured thereto, means at the upper and lower ends of said tubular barrel to bear against said working barrel and scrape the same free of sand, and hard metal ex- 120 pansion rings between said scraping means.

3. In a pump, a working barrel, a plunger reciprocable therein, a tubular section on 125 said plunger, upwardly flaring cups thereon positioned to bear against said working barrel at the upper end thereof and down-

wardly flaring cups at the lower end in combination with piston rings on said section between said cups, said rings being clamped between said cups and adapted to press resiliently against said working barrel.

4. In a pump, a working barrel, a plunger therein, upwardly flaring cups at the upper end and downwardly flaring cups at the lower end thereof, said cups adapted to 10 scrape the inner face of said working barrel, and means between said cups adapted to make a close fit with said working barrel comprising sets of slidable rings having fitted thereon at one end resilient expanding 15 piston rings.

5. In a pump plunger the combination of a tubular body, scraping cups at each end thereof, and resilient expanding rings clamped between said cups on said body.

20 6. In a pump, a working barrel, a plunger

reciprocable therein and having cups and expanding rings thereon, in combination with means to hold said rings contracted while said plunger is introduced into said working barrel, comprising a guide barrel 25 having a detachable bell shaped mouth thereon, said guide barrel being of the same internal diameter as said working barrel.

7. In a pump, a working barrel, a plunger reciprocable therein, a tubular section on 30 said plunger, upwardly flaring cups at the upper end and downwardly flaring cups at the lower end of said section, a plurality of resilient expanding rings on said barrel between said cups and common means to clamp 35 said cups and rings in place on said plunger.

In testimony whereof, I hereunto affix my signature, this the 8th day of July, 1921.

GERALD R. LIVERGOOD.
